Aargau, Switzerland

Filed Sept. 24, 1962, Ser. No. 225,807
5 Claims. (Cl. 103—161)

Hydraulic pressure pumps and motors are required to convey appropriate pressure fluids by displacing them from enclosed chambers or to supply such pressure fluids to such chambers for conversion into mechanical power. Constructions have accordingly been devised in which the piston stroke can be varied to control the swept volumes delivered per unit of time. Devices of this kind have become quite popular and are technically satisfactory, but the controlled stroke feature makes the transmission elements of such machines expensive since the bearing elements which transmit the hydraulic forces from the displacing system to the rotating system must themselves be adjusted. There has long been a requirement for systems which will vary the effective swept volume but which are free from the complications of the controlled stroke feature. A number of suggestions have been made. For instance, it is known to vary the volume of high-pressure pumps by arranging for the valve opening and closing times to be shifted in time relatively to piston stroke—the so-called sequence control method. It is also known to construct the swept volume from a number of displacement elements, the phase of which relatively to the transmissions displacing them can be shifted—i.e., different volumes can be delivered. To date, however, it has proved impossible to construct pumps and motors for pressures above 200 atmospheres absolute which will operate control systems of this kind and which are of reliability comparable to the conventional stroke-controlled pressure pumps.

This invention helps to solve the problem. According to the invention, although the complete machine is of simple construction two control features are provided—control by phase sequence, and control by variation of the swept volume by phase differences between two displacement elements operating in a communicating chamber. The combination of these two features, each of which is known per se, enables variation of delivery direction to be combined with the advantage of control of the swept volume. Stroke-controlled pumps in which the piston stroke can be controlled in the driving mechanism operate to either hand—i.e., in either direction of conveyance. If the displacement chamber were to be controlled by the difference between the phases of two elements, there would be no possibility of changing the direction of rotation in this way, since the physical relationship of the resultant strokes relatively to the control surface remains constant. However, this difficulty is overcome by the combination according to the invention of phase sequence control with displacement control, and a pump or a motor can be devised without any extra outlay but having the controllability of stroke-regulated machines but being simpler in construction and cheaper to construct than stroke-regulated machines.

For a better understanding of the invention and to show how the same may be carried into effect, reference may now be made to the accompanying drawing wherein:

FIG. 1 is a longitudinal section through a radial piston machine constructed as a pump;

FIG. 2 is a cross-section taken along the line II—II of FIG. 1;

FIG. 3 is a longitudinal section through a radial piston machine constructed as an infinitely variable transmission, and

2

FIG. 4 is a longitudinal section through a two-stage piston of the radial piston machine.

The pump illustrated in FIG. 1 comprises a rotor 1 which is driven by a shaft 2 and which is centered on a control member (control surface) 3 rigidly secured to a casing 4 closed by a cover 5. Two-piece pistons 6, 6' engage by way of pivots 7 and rollers 8 with cams 9 and 10. Through the agency of hand wheels 13, gearing 11 and worms 12, the cams 9, 10 can be adjusted angularly. The delivery chambers of the pistons 6 are interconnected by a duct 14. The control surface 3 has four ducts 15, 15' which are interconnected by cross-connections 16, 16' and which extend to inlet or outlet apertures 17 and 17'. Cylinder chambers 18 have through connections to one another through ducts 19. The fluid is supplied and removed, and the control is effected, by way of perforations 20, 20' in the control surface 3.

The shape of the two cams 9 and 10 can be imagined as the shape arising out of one complete sinusoidal oscillation being superimposed upon a circle. The two cams 9 and 10 are offset by 90° from one another and so the pistons 6, 6' move to opposite hands, with the result that the fluid in the compression chamber performs merely an oscillatory motion. When the two cams 9 and 10 are in the same position so that they overlap, the two pistons perform a parallel movement to provide maximum delivery. To reverse the flow of liquid, the two cams 9 and 10 are rotated together through 90° so that their position relatively to the perforations or apertures 20 and 20' is so altered that they change over from the intake side to the delivery side. The top cylinder chambers 18 of the stepped pistons 6 and 6' are interconnected by a ring duct 19. Since the total volume in these chambers always remains the same, the liquid contained in such chambers applies a restoring force to the pistons in addition to centrifugal force which is also operative radially.

FIG. 3 illustrates a radial piston machine constructed as transmission. The construction of the pump is identical to the construction hereinbefore described, but the ducts 15 and 15' extend directly to the motor which is similar in construction to the pump except that the second set of parallel-guided pistons is omitted. In this embodiment the fluid moves in a closed circuit from the pump to the motor and back. Motor speed is controlled by controlling the pump in the manner hereinbefore described, and the direction of rotation of the motor is reversed by reversing the direction of the liquid flow. The speed, power and torque of the motor can be adjusted by adjustment of the cam 10'.

FIG. 4 illustrates the two-piece stepped piston 6 and 6' with its pivot 7 and roller 8. A connecting element 21 is loaded by springs 22—shown here as spring washers—to ensure that the piston 6 is not subjected to the very high pressures associated with the passage of the piston 6 over the closed parts of the control surface 3. The force of the springs 22 is adapted to the required maximum delivery pressure absorbing the high stresses reduces the wear.

60 What I claimed is:

1. A fluid power device comprising, in combination, a housing; a rotor rotatably mounted in said housing and formed with a pair of axially spaced radial bores; a piston reciprocable longitudinally of each bore in operative association with pressure fluid in the respective bore; a stationary control member having angularly displaced fluid inlet and outlet passages; duct means connecting each bore to passage means in said control member connected to one of said passages; a pair of angular control cams in said housing substantially concentric with said rotor and each having a substantially circular outer

periphery and a sinusoidal inner periphery, each cam being radially aligned with a respective piston; a cam follower connected to the outer end of each piston and engaged with the inner periphery of the associated cam, for reciprocation of the pistons during relative rotation of said rotor and said cam; and a pair of independently actuatable adjusting means each operative to effect angular adjustment of a respective cam independently of the other cam to select the absolute phase relation of the associated respective cam to said control member and the relative phase relation of said cams to each other.

2. A fluid power device, as claimed in claim 1, in which said radial bores are disposed in a common radial plane of said rotor; each bore of said pair being connected to the same passage means in said control member; whereby, by relative angular adjustment of the respective cams, the time relation of the displacement of the pair of pistons may be selected at will.

3. A fluid power device, as claimed in claim 2, in which said cams are substantially identical and each cam effects two reciprocations of its respective piston during each revolution of said rotor.

4. A fluid power device, as claimed in claim 1, includ-

ing resilient means interconnecting each cam follower to its associated piston to even out the compression peaks arising during operation of said device.

5. A fluid power device, as claimed in claim 4, in which each cam follower includes a support formed with an outwardly opening recess whose inner end is formed with a bore coaxial with the respective piston but of less diameter than the respective piston; an element connecting each support to its associated piston and in the form of a headed member having a stem extending through the bore in the support and connected to the piston, the head of said element being disposed in said recess; and compression spring means disposed between the head of said element and the inner wall of said recess and between the outer surface of said support inner end and the outer end of the associated piston.
